TOY MONKEY FIGURE

Jennifer Jenkins Houser, 520 1 E., Apt. 3,
Provo, Utah 84601

Filed Dec. 28, 1970, Ser. No. 26,654

Term of patent 14 years

Int. Cl. D21—01

U.S. Cl. D34—2

FIG. 1

FIG. 2

FIG. 1 is a left front perspective view of the toy monkey figure embodying my new design;

FIG. 2 is a right rear perspective view as viewed from the bottom.

I claim:

The ornamental design for a toy monkey figure, substantially as shown.
